UNITED STATES PATENT OFFICE.

CHESTER H. JACKSON, OF PORTLAND, MAINE.

WEATHERPROOF POLE-SWITCH.

SPECIFICATION forming part of Letters Patent No. 761,230, dated May 31, 1904.

Application filed May 29, 1903. Serial No. 159,345. (No model.)

To all whom it may concern:

Be it known that I, CHESTER H. JACKSON, a citizen of the United States, residing at Portland, in the county of Cumberland and State 5 of Maine, have invented new and useful Improvements in Weatherproof Pole-Switches, of which the following is a specification.

My invention relates to new and useful improvements in weatherproof pole-switches for 10 electric systems; and its object is to provide a casing of non-conducting material within which is affixed a socket which is connected to one wire of a circuit.

A further object is to provide a reciprocating plunger connected to the other wire of the 15 circuit and which is adapted to be slid into engagement with the socket to complete the circuit.

A further object is to employ means for 20 breaking the circuit in oil, so that the current will not arc across the plunger and socket; and another object is to provide a locking device whereby the withdrawal of the plunger from the casing is prevented.

With the above and other objects in view 25 the invention consists in the further novel construction and combination of parts hereinafter more fully described and claimed, and illustrated in the accompanying drawings, 30 showing the preferred form of my invention, and in which—

Figure 1 is a side elevation of the switch. Fig. 2 is a section on line 2 2, Fig. 1. Fig. 3 is a view similar to Fig. 2, but showing the 35 plunger removed from its socket. Fig. 4 is a section on line 4 4, Fig. 3, and Fig. 5 is a section on line 5 5, Fig. 3.

Referring to the figures by numerals of reference, 1 is a casing preferably formed of porcelain or any other suitable non-conducting 40 material, and this casing has a cylindrical stem 2 extending from one side thereof and screw-threaded, so as to permit the casing to be readily fastened to a pole or other suitable 45 supporting device. An arm 3 also projects from this casing, and one of the wires 4 of an electric circuit is adapted to extend therethrough. The compartment 5, formed within the casing, is reduced in diameter at its upper

end, and said reduced portion receives a plug 50 6, formed of suitable conducting material and having a flange 7 therearound, which bears upon a tube 8 of hard rubber or other non-conducting material. This tube bears upon a base-plate 9, which is fastened within the 55 lower end of the casing, the compartment 5 being enlarged to receive the same. The plate is preferably secured in position within the lower end of the casing by means of screws 10. A socket 11 extends downward from and 60 is integral with the plug 6, and this socket is slotted longitudinally, as shown at 12, and the lower end thereof is inclosed by a coiled spring 13, which serves to hold the slots normally closed. The chamber formed by the tube 8 65 is partly filled with oil for the purpose of insulation to destroy the arc which follows the plunger when it is pulled from the socket. The inner end of the wire 4 is secured within the upper end of plug 6 and is electrically 70 connected thereto.

A screw-threaded aperture 14 is formed in the center of the base-plate 9 and receives a tubular nut 15, within which is arranged packing 16, which incloses a plunger 17, slidably 75 mounted within the nut and extending into the tube 8. A disk 18, having a concaved inner surface, is arranged within the nut 15 and bears upon packing 16, and this disk is held in place by a nut 19, which extends over and 80 is threaded upon the outer end of the nut 15. The outer end of the nut 19 is slotted longitudinally and is inclosed by a coiled spring 20, which causes the slotted end of the nut to bear firmly upon the plunger 17. 85

A handle 21 is formed at the outer end of plunger 17, and a slot 22 is formed in the inner end of the plunger, and pivoted within this slot is a dog 23, which is normally pressed outward by means of a spring 24. The second wire 25 of the circuit is secured to the base-plate 9, as shown in Fig. 4, and this wire, as well as the wire 4, is provided with a coupling-sleeve 26, whereby the line-wires may be readily connected thereto. 90

When it is desired to complete the circuit between wires 4 and 25, the plunger 17 is pressed inward by means of handle 21, and the 95

inner end thereof is brought into contact with and slides into the socket 11, thereby spreading the slotted end thereof. A circuit is thus established from wire 4 through plug 6, socket 11, plunger 17, nuts 19 and 15, and base-plate 9 to the wire 25. To break the circuit, it is merely necessary to draw the plunger 17 outward until withdrawn from the socket 11, and the oil within the tube 8 prevents any possible arc between the plunger and the socket. The dog 23 will prevent the plunger 17 from being completely withdrawn from the casing 1.

A switch constructed in accordance with my invention is absolutely weatherproof and is therefore particularly adapted for use upon poles and their exposed supports.

In the foregoing description I have shown the preferred form of my invention; but I do not limit myself thereto, as I am aware that modifications may be made therein without departing from the spirit or sacrificing the advantages thereof, and I therefore reserve the right to make such changes and alterations as may fairly fall within the scope of my invention.

Having thus described my invention, what I claim as new, and desire to secure by Letters Patent, is—

1. In an electric switch, the combination with a casing, of a socket therein at one end and electrically connected to one wire of a circuit, a plunger slidably mounted in the other end of the casing and electrically connected to the second wire of a circuit, said plunger being adapted to engage the socket, a dog pivoted within a slot in the plunger, and a spring within the slot for holding the dog normally projected from the slot.

2. In a switch of the character described, the combination with a casing having a socket therein adapted to be electrically connected to one wire of a circuit; of a base-plate within the casing adapted to be electrically connected to a second wire, a plunger slidably mounted within the base-plate and electrically connected therewith, said plunger being adapted to project into the socket to complete a circuit, a dog pivoted within a slot in the plunger and means for holding the dog normally projected from the slot.

3. The combination with a casing having fastening means integral therewith, of a base-plate secured to one end of the casing, a plunger slidably mounted therein, a nut interposed between the plunger and base-plate, packing within said nut, a concaved disk within the nut and inclosing the plunger, a retaining-nut for said disk bearing upon the plunger, an insulating-tube within the casing and upon the base-plate, a longitudinally-slotted socket supported thereby in the path of the plunger, means for holding the slots normally closed, and means for preventing the withdrawal of the plunger from the base-plate.

4. The combination with a casing having

fastening means integral therewith; of a base-plate secured to one end of the casing, a plunger slidably mounted therein, a nut interposed between the plunger and base-plate, packing within said nut, a concaved disk within the nut and inclosing the plunger, a retaining-nut for said disk bearing upon the plunger, an insulating-tube within the casing and upon the base-plate, a longitudinally-slotted socket supported thereby in the path of the plunger, and means for preventing the withdrawal of the plunger from the base-plate.

5. The combination with a casing, of a base-plate secured to one end of the casing, a plunger slidably mounted therein, a nut interposed between the plunger and base-plate, packing within said nut, a disk within the nut and inclosing the plunger, a retaining device for the disk having its outer end slotted, a coiled spring embracing the slotted portion of the retaining device, an insulating-tube within the casing and upon the base-plate, a socket supported thereby in the path of the plunger, and means for preventing the withdrawal of a plunger from the base-plate.

6. The combination with a casing having fastening means integral therewith, of a base-plate secured to one end of the casing, a plunger slidably mounted therein, a nut interposed between the plunger and base-plate, packing within said nut, a concaved disk within the nut and inclosing the plunger, a retaining-nut for said disk bearing upon the plunger, an insulating-tube within the casing and upon the base-plate, a longitudinally-slotted socket supported thereby in the path of the plunger, a coiled spring embracing the lower end of the slotted socket, and means for preventing the withdrawal of the plunger from the base-plate.

7. The combination with a casing, of a base-plate secured to one end of the casing, a plunger slidably mounted therein, a nut interposed between the plunger and base-plate, packing within said nut, a disk within the nut and inclosing the plunger, a retaining device for the disk having its outer end slotted, and means to cause the retaining device to bear firmly on the plunger.

8. In an electric switch, a casing having a compartment therein, a plate at one end of the compartment, a plug in the opposite end, an insulating-tube resting upon the plate, a socket extending from the plug and within the tube, and a plunger extending through the base-plate and adapted to engage the socket.

9. In an electric switch, a casing having a compartment therein, the diameter of the upper portion of said compartment being reduced, a base-plate at the lower end of the compartment, a tube resting on the base-plate, a plug in the reduced portion of the compartment, a flange on the plug adapted to bear upon the tube, a socket formed integral with

the plug, extending downward within the tube, and a plunger extending through the base-plate and adapted to engage the socket.

10. In an electric switch, a casing having
5 a compartment therein, a threaded stem extending from the casing, an arm projecting from the casing, a base-plate fastened within the casing, a wire of an electric circuit connected to the base-plate, a non-conducting
10 tube resting on the base-plate, a plug within one end of the compartment bearing on the tube, a socket depending from the plug with-

in the tube, a second circuit-wire passing through the arm of the casing, and connected to the socket, a plunger extending through 15 the base-plate and adapted to engage the socket, and an insulating fluid within the casing.

In testimony whereof I affix my signature in presence of two witnesses.

CHESTER H. JACKSON.
